UNITED STATES PATENT OFFICE

2,434,375

APPARATUS FOR FORMING CONTAINER HEADS

Raymond H. Van Saun, Berkeley, Calif., assignor
to Container Corporation of America, Chicago,
Ill., a corporation of Delaware

Application July 14, 1944, Serial No. 544,995

3 Claims. (Cl. 113—42)

1

This invention relates, in general, to an apparatus for forming container heads or the like, and has particular relation to an apparatus adapted for the production of container heads from sheet material, such as paperboard, fiberboard, or like material, by means of a plurality of drawing operations.

While the particular apparatus which I shall describe hereinafter in connection with the drawings is adapted for producing container heads circular in form, it is to be understood that these articles may be shaped otherwise within the broader aspects of the present invention.

One of the main objects of the present invention is to provide an improved apparatus for producing quickly, efficiently, and relatively inexpensively container heads which in their production require a plurality of drawing operations.

Another object of the invention is to provide an improved apparatus, and more particularly an improved drawing press, upon which a plurality of drawing operations may be performed on a blank of paperboard, fiberboard, or similar sheet material without the necessity of handling the blank between such operations.

Another object of the invention is to provide for performing the drawing operations without weakening the material from which the article is produced; also for performing these operations in an improved manner and on a single machine.

Another object of the invention is to provide an improved arrangement of the drawing and shaping members and other parts; also an improved correlation between these parts and the operating means therefor for accomplishing the purposes set forth.

It is a further and more specific object of the invention to provide in a drawing press of the class described a pair of draw rings, one having movement relative to the other, and a plurality of cooperating drawing and shaping members having movement relative to each other; also movement in unison and movement relative to said draw rings for accomplishing the purposes set forth.

Another more specific object of the invention is to provide a drawing press for the production from a sheet of the class described of a circular container head having a marginal portion provided with an annular groove adapted to receive the adjacent end of a cylindrical container wall; also a downwardly extending peripheral flange adapted to lie outside the wall of the container, and an annular depression adjacent and inwardly of said marginal portion.

Further objects, advantages and uses of the invention will become apparent from the following detailed description, taken in connection with the accompanying drawings in which:

Figure 1 is a front elevational view of one form

of my improved drawing press for forming container heads or the like in accordance with the present invention;

Figure 2 is a vertical sectional view through the draw rings and the drawing and shaping members and adjacent parts, partially in elevation, and on an enlarged scale;

Figures 3 to 7, inclusive, are simplified fragmentary sectional views illustrating the positions of the draw rings and the cooperating drawing and shaping members during various stages of production of a container head;

Figure 8 is a sectional view similar to Figure 2 but in simplified form, showing a modification of the apparatus shown in Figure 2; and

Figures 9 and 10 are simplified fragmentary sectional views illustrating subsequent positions of the drawing and shaping members of Figure 8.

Referring first to the embodiment of the invention illustrated in Figures 1 to 7, inclusive, of the drawings, the reference character 10 designates, generally, a frame comprising uprights angle iron members 11, horizontal angle iron members 12 extending from front to rear of the frame, and further horizontal angle iron members 13 extending from side to side of the frame at right angles to the members 12. The members 12 are bolted or otherwise suitably secured to the upright members 11, and the members 13 are bolted or otherwise secured to the members 12.

The container head is made from sheet material 14, such as paperboard, fiberboard, or like material, which is fed between lower and upper draw rings designated, in general, at 15 and 16 respectively. The sheet material 14 is adapted to be held marginally by the draw rings 15 and 16 with the area of the sheet material within the draw rings positioned between lower and upper forming and shaping or die members 17 and 18.

The sheet material may be formed of several plies of material laminated together, and the container head may be drawn or shaped while the thermoplastic or other adhesive is soft so that the plies may slip on one another during the drawing and shaping operation and thus better preserve the fibrous structure of each ply. This may vary widely insofar as the apparatus of the present invention is concerned, and, therefore, for the purpose of simplifying the disclosure, the laminated form of the sheet material is not illustrated in the drawings.

The lower draw ring 15 is secured in place on a supporting base member 19 carried, for example, by adjacent angle irons 13. Base member 19 has an axial opening 20. The cooperating upper draw ring 16 is carried by a yoke member 21 mounted for vertical movement on guide pins 22 screwed at their lower ends into upstanding bosses on the supporting base 19. The upper draw ring 16 has an inner radius larger than the

inner radius of the lower draw ring 15 by about the thickness of the finished wall of the container head. An annular insulating member 23 is interposed between the bottom of the draw ring 15 and the base member 19 to prevent loss of heat by conduction from the ring 15. A similar annular insulating member 24 is interposed between the top of the ring 16 and the member 21 to prevent loss of heat from the ring 16.

While the draw rings 15 and 16 are shown of one piece construction in the simplified views, Figures 3 to 7, inclusive, each of these rings preferably comprises inner and outer sections as shown in Figure 2. The two sections of the lower ring 15 are secured by bolts 25 or other suitable means to an annular member 26, and the two sections of the upper ring 16 are secured by bolts 27 to an annular member 28. The lower draw ring 15 has an upwardly facing clamping surface and an upwardly extending annular cutting or shearing edge 29 surrounding said clamping surface. The upper draw ring 16 has a cooperating downwardly facing clamping surface and a lower outer annular edge 30 adapted to cooperate with the cutting edge 29 to cut a circular blank from the sheet material 14 when the upper draw ring 16 descends toward the lower ring 15. The draw rings 15 and 16 may be provided internally thereof with electric or other suitable heaters 32 and 33, respectively, of annular or other suitable form.

The lower drawing and shaping member is in the form of a die member 34 fastened, for example, by bolts 35 and a flanged collar 36 to the upper end of a shaft 37. The shaft 37 is adapted to be actuated to raise and lower the die member 34 by suitable means, for example, by movement of a piston 38 in a lower air or fluid cylinder 39 carried by adjacent angle irons 13. The shaft 37 extends downwardly from the die member 34 and axially into the cylinder 39, and is fastened at its lower end to the piston 38. The cylinder 39 is shown as having air or fluid ducts or tubes 40 and 41 connected therewith, as well understood in the art.

As shown in detail in Figure 2, the die 34 is preferably constructed of several sections secured together by annularly spaced bolts 42 or other fastening means. Electric or other suitable heaters 44, of annular or other form, are preferably mounted in downwardly opening annular recesses in the intermediate section of the lower die, and may be held in place by the lower section or cover plate of this lower die, between which and the flanged collar 36 an annular insulating member 45 is interposed. A further annular insulating member 46 is interposed between the bottom of the lower section of the die 34 and the supporting base 19. These insulating members 45 and 46 prevent loss of heat by conduction from the bottom of the lower die. The upper surface of the intermediate section of the lower die has one or more annular grooves 48 from which a plurality of annularly spaced vertical passageways 49 extend downwardly through the lower die. These passageways vent from the space between the bottom of the sheet material 14 and the upper surface of the lower die vapor or the like which may be emitted from the sheet 14 or from adhesive between plies thereof in the drawing and shaping operation.

The outer periphery of the lower die 34 has sliding fit with the inner surface of the lower draw ring 15, and, being of approximately the same diameter as the inner diameter of the lower draw ring 15, has an external diameter

smaller than the inner diameter of the upper draw ring 16 by about twice the thickness of the finished wall of the container head. The upper surface of the lower die 34 is provided with an annular forming or shaping well or channel 52 the outer surface of which is formed by an upstanding annular portion 53. The annular well or channel 52 and the upstanding annular portion 53 are preferably formed in the third section or forming head insert of the lower die, which insert may, if desired, be hardened, and is adapted to be removed and replaced, as well known in the art.

The yoke member 21 and the upper draw ring 16 carried thereby are adapted to be raised and lowered by suitable means, for example, by movement of a piston 55 in an intermediate air or fluid cylinder 56 carried by adjacent angle irons 13. The piston 55 has a tubular shaft 57 which extends downwardly through the lower end of the cylinder 56 and is fastened at its lower end to the yoke member 21, so that movement of the piston 55 within the cylinder 56 will lower and raise the yoke member 21 and the upper draw ring 16 with an accompanying sliding movement of the yoke member 21 on the guide pins 22. The cylinder 56 has air or fluid ducts or tubes 59 and 60 connected therewith.

The upper drawing and shaping member is in the form of a die member or plunger 62 fastened by bolts 63 and a flanged collar 64 to the lower end of a shaft 65. The shaft 65 is adapted to be actuated to raise and lower the die or plunger member 62 by movement of a piston 66 in an upper air or fluid cylinder 67 carried by adjacent angle irons 13. The shaft 65 extends upwardly through the tubular shaft 57, axially through the fluid cylinder 56 and into the fluid cylinder 67 wherein it is fastened at its upper end to the piston 66. The cylinder 67 is shown as having air or fluid ducts or tubes 69 and 70 connected therewith.

As shown in Figure 2, the upper die member or plunger 62 has a depending annular drawing and shaping portion 72 which is adapted to enter the channel 52 and to have drawing and shaping cooperation with the lower die 34 when the upper die or plunger 62 descends into cooperation with the lower die. The upper die 62 has an external diameter which is smaller than the internal diameter of the upstanding annular portion 53 of the lower die 34 by about the thickness of the sheet material 14. The tapered inner annular surface 73 of the depending portion 72 cooperates with the correspondingly tapered inner annular surface of the channel 52 when the upper die is brought into cooperation with the lower die.

The lower surface of the upper die or plunger 62 has one or more annular grooves 75 from which a plurality of annularly spaced vertical passageways 76 extend upwardly through the upper die. These passageways 76 vent, from the space between the top of the sheet material 14 and the lower surface of the upper die, vapor or the like which may be emitted from the sheet 14 or from adhesive between plies thereof in the drawing and shaping operation. Like the grooves 48, the grooves 75 are preferably relatively small so as not to produce formations in the sheet 14, although this may, of course, vary. Electric or other suitable heaters 78, of annular or other form, are preferably mounted in upwardly opening annular recesses in the upper die 62, and may be held in place by the upper section or

cover plate 79 secured to the upper die by bolts 80 or other fastening means and also by the bolts 83. An annular insulating member 82 is interposed between the plate 79 and the flanged collar 64 to prevent loss of heat by conduction from the upper die.

Mounted on one side of the frame of the press is a control panel 84 which may be provided with air or fluid cylinder valves (not shown), and, if desired, air or fluid cylinder speed control valves (not shown) for the respective air or fluid cylinders 39, 56 and 67. The heaters 32, 33, 44, and 78 may be connected by means of conductors 85 to any suitable source of current, which may be a 220 volt circuit or any other suitable circuit.

In drawing and forming a container head or the like from the sheet material 14, the following sequence is followed:

With the upper draw ring 16 and upper die member 62 in raised position and the lower die member 34 in its lowered position the sheet material 14 is fed between the upper and lower draw rings. With the sheet 14 so positioned, the valve means for the cylinder 56 is operated to lower the yoke member 21 and cause the upper draw ring 16 to descend on the sheet 14 or web of plies. The cooperation of the cutting edge 29 with the edge 30 on the lower ring 15 cuts out a circular blank from the sheet 14. The ring 16 continues downward until the blank is held marginally therebetween, the distance remaining between the upper and lower draw rings 15 and 16 being preferably slightly greater than the caliper of board or material to be drawn.

The draw rings 15 and 16 then remain stationary, and the valve means for the cylinder 67 is operated to move the upper die member 62 downwardly into drawing and shaping cooperation with the lower die member 34 as shown in Figure 3. This forces the blank 14 into the annular well or channel or 52, thus forming an annular well in the blank 14 corresponding with the shape of the well 52 of the die 34 and the cooperating portion 72 of the die 62. The outer margin of the blank 14 is drawn inwardly to some extent from between the draw rings 15 and 16 in this operation, but not sufficiently to weaken the material 14.

The control valve means is then operated to move the lower and upper dies 34 and 62 upwardly in unison with the blank 14 therebetween. This draws the remaining marginal portion of the blank 14 from between the draw rings 15 and 16, and the passage of the lower die 34 into or through the upper draw ring 16 downturns the marginal portion of the blank around the upstanding annular portion 53 of the lower die, and between it and the inner surface of upper draw ring 16 to form on the container head a marginal portion provided with an annular groove adapted to receive the adjacent end of the wall of the container (not shown). The positions of the upper and lower die members upon completion of this stage of the operation are shown in Figure 4.

The next step is to operate the control valve means for the cylinder 56 to raise the upper draw ring 16 to approximately the position shown in Figure 5, whereupon the control valve means for the cylinder 67 is operated to raise the upper die member 62 to approximately the position shown in Figure 6. Then by operating the control valve means for the cylinder 39, the lower die member 34 is caused to descend to its lowered position. This frees the drawn and shaped con-

tainer head shown at a in Figure 7; the finished container head a being supported, for example, marginally on the lower draw ring at 88 for withdrawal or ejection from the press.

Referring to Figure 7, the finished container head a has the annular well b, the marginal portion provided with the annular groove c adapted to receive the adjacent end of the wall of the container and the downwardly extending peripheral flange d adapted to lie outside the wall of the container.

In the modified form of apparatus shown in Figures 8, 9, and 10, the lower and upper draw rings 15' and 16', the upper die or plunger member 62', and the yoke member 21' and guide pins 22' therefor are similar to the corresponding parts of the preceding embodiment of the invention. The means for actuating the upper draw ring and the upper die may also be similar to the means shown in Figure 1, or of other suitable form.

The lower die means of this modified form of the invention comprises a pair of drawing and shaping die members 90 and 91. The die member 90 is fastened by bolts 92 and a flanged collar 93 to the upper end of a shaft 94. The shaft 94 extends through a collar or tubular actuating member 95 for the other lower die member 91. The collar 95, which has sliding movement on the shaft 94, has an upper end of reduced outer diameter which extends into an axial opening in the die member 91.

The outer periphery of the die member 91 has sliding fit with the inner surface of the lower draw ring 15' and is provided with an upstanding annular portion 96. The inner radius of the upstanding annular portion 96 is larger than the outer radius of the upper die or plunger member 62' by about the thickness of the finished wall of the container head. The upper draw ring 16' has an inner radius larger than the inner radius of the lower draw ring 15' by about the thickness of the finished wall of the container head. The outer periphery of the lower die member 91, being approximately of the same diameter as the inner diameter of the lower draw ring 15', has an external diameter smaller than the inner diameter of the upper draw ring 16' by about twice the thickness of the finished wall of the container head.

As in the preceding embodiment of the invention, the upper die 62' has a depending annular drawing and shaping portion 72' provided with a tapered inner annular surface 73'. In this case the upper member 90 of the two lower die members has an upstanding drawing and shaping portion 97 provided with an outer annular surface 98 tapered to conform with the taper of the surface 73' for cooperation therewith.

In this latter embodiment of the invention, the operating sequence is as follows:

With the upper draw ring 16' and upper die 62' in raised position and the lower die members 90 and 91 in their lowered positions, the sheet material 14' is fed between the draw rings. With the sheet material 14' so positioned, the upper draw ring 16' is caused to descend on the sheet 14'. The cooperation of the cutting edge 29' with the edge 30' cuts out a blank from the sheet. The ring 16' continues downwardly to position to hold the blank marginally, as in the preceding embodiment of the invention.

The draw rings 15' and 16' then remain stationary, and the upper die 62' is moved downwardly into drawing and shaping cooperation

with the upper member 90 of the two lower die members, as shown in Figure 8. This draws and shapes the inner portion of the annular well formed in the container head.

Then, with the parts positioned as shown in Figure 8, the lower member 91, of the two lower dies 90 and 91, is moved upwardly relative to the die 90. In this movement, the upstanding annular portion 96 of the lower member 91 moves over the outer periphery of the upper die 62' and completes the drawing and shaping of the outer portion of the annular well formed in the container head, as shown in Figure 9. Then with the parts in this position and with the die 91 in engagement with the die 90 at 100, the die members 90, 91 and 62' are moved upwardly in unison to approximately the positions shown in Figure 10. This draws the remaining marginal portion of the blank 14' from between the draw rings 15' and 16', and the movement of the die 91 into or through the upper ring 16' downturns the marginal portion of the blank around the upstanding annular portion 96 of the die 91 to complete the drawing and shaping of the container head.

It is to be understood that the dies 90, 91, and 62' and the draw ring 16' of the embodiment of the invention shown in Figures 8, 9, and 10 may be actuated by air or fluid cylinder and piston means, as disclosed in connection with the preceding embodiment of the invention or in any other suitable or preferred manner.

I do not intend to be limited to the precise details or to the precise modifications shown and described, as variations in the details and other modifications are contemplated within the scope of the appended claims.

I claim:

1. Apparatus for forming a container head from a blank of paperboard or the like, comprising first and second draw rings for holding the blank at the margin thereof, said first ring having an internal radius greater than that of said second ring by substantially the thickness of said blank, a plurality of die members movable axially of said rings, one of said die members being disposed in said first ring and another of said die members being disposed with a sliding fit in said second ring in opposed relation to said one die member and having an axially extending peripheral projection, said one die member having an external radius smaller than the internal radius of said first ring by substantially the thickness of said projection plus twice the thickness of said blank, and means for moving said one die member independently and for moving said plurality of die members in unison, whereby the central portion of said blank may be shaped between opposed die members by movement of said one die member in one direction and the marginal portion of the blank may be shaped between said one die member, said projection, and said first ring by movement of said die members in the opposite direction to dispose said projection between the periphery of said one die member and the inner periphery of said first ring.

2. Apparatus for forming a container head from a blank of paperboard or the like, comprising a fixed draw ring, a movable draw ring having an internal radius greater than that of said fixed ring by substantially the thickness of said

blank and movable in opposition to said fixed ring to hold the marginal portion of said blank therebetween, a first die member within said fixed ring having a diameter substantially equal to the internal diameter thereof, an axially extending peripheral projection on said first die member, a second die member within said movable ring having a radius smaller than the integral radius of said movable ring by substantially the thickness of said projection plus twice the thickness of said paperboard and movable in one direction into forming relation with said first die member to shape the central portion of said blank, said first and second die members being movable in said forming relation in the opposite direction to dispose said projection spaced between the periphery of said second die member and the inner periphery of said movable ring with said marginal portion of the blank drawn thereabout from between said rings, and separate means for actuating said die members and said movable draw ring.

3. Apparatus for forming a container head from a blank of paperboard or the like, comprising a pair of opposed draw rings for holding the blank at the margin thereof, a first of said rings having an internal radius greater than that of the second of said rings by substantially the thickness of said blank, a first die member in said first ring, an annular second die member 25 slidingly fitting in said second ring and having a peripheral axially extending projection, a third die member within said second die member in opposition to said first die member, said first die member, having a radius smaller than the internal radius of said first ring by substantially the thickness of said projection plus twice the thickness of said blank, said die members being movable axially in said rings independently and together, whereby said central portion of said blank 30 may be shaped between said first and third die members by movement of said first die member in one direction and the marginal portion of the blank may be shaped between said projection and the external periphery of said first die member and internal periphery of said first ring by movement of said die members in the opposite direction, and means for moving said first die member in said one direction and for moving said die members in the opposite direction.
